(57) **CLAIM**

The ornamental design for a cavitation mixer as shown and described.

DESCRIPTION

FIG. 1 is a front perspective view of a cavitation mixer of the present design;

FIG. 2 is a side view thereof;

FIG. 3 is a front view thereof;

FIG. 4 is a rear view thereof; and,

FIG. 5 is a perspective view thereof, showing the cavitation mixer in a state of use in its environment.

The broken lines in the figures illustrate portions of the cavitation mixer that form no part of the claimed design.
